[57] CLAIM

The ornamental design for a tool caddy for a tank type vacuum cleaner, as shown and described.

DESCRIPTION

FIG. 1 is a front, right side perspective view of a tool caddy for a tank type vacuum cleaner showing my new design;

FIG. 2 is an enlarged rear perspective view thereof;

FIG. 3 is a top view thereof;

FIG. 4 is a bottom view thereof;

FIG. 5 is a front view thereof;

FIG. 6 is a rear view thereof;

FIG. 7 is a side view thereof, the opposite side view being a mirror image; and,

FIG. 8 is a cross sectional view thereof at cross section markings 8 in FIG. 3.

The environmental material shown in broken lines is not part of the design.

FIG.1

FIG.2

FIG.3

FIG.4

FIG. 5

FIG. 6

FIG. 7
